UNITED STATES PATENT OFFICE.

WILLIAM H. WELCH, OF CLEVELAND, OHIO, ASSIGNOR TO THE CLEVELAND MACHINE & MANUFACTURING COMPANY, OF CLEVELAND, OHIO, A CORPORATION OF OHIO.

MECHANICAL MOVEMENT.

1,110,977.

Specification of Letters Patent. Patented Sept. 15, 1914.

Application filed July 9, 1913. Serial No. 773,101.

To all whom it may concern:

Be it known that I, WILLIAM H. WELCH, a citizen of the United States, residing at Cleveland, in the county of Cuyahoga and State of Ohio, have invented certain new and useful Improvements in Mechanical Movements, of which the following is a specification.

My invention relates to improvements in mechanical movements, and more particularly to that class or type wherein a reciprocating movement is imparted by a continuously revolving crank or shaft and a pause or dwell is desired during a portion of the revolution of the crank or shaft, or in other words,—wherein only during a certain portion of the revolution of the driving or continuously revolving element is motion transmitted to the reciprocating member.

20 The present embodiment of the invention is particularly designed and adapted for use in connection with drawing or stamping presses wherein the blank or sheet to be operated upon is gripped against the die by a blank holder and held there during the operation of the plunger or male die.

In presses of this general character, the plunger or male die is usually connected to a crank on a driving shaft which at every operation of the press forces the plunger down and lifts it again. The blank holder through which the plunger moves descends in advance of the plunger until it reaches the blank, and after pressing and holding the latter firmly against the fixed die, it pauses or dwells in this position in order to firmly hold the blank during the action of the plunger and then ascends either with or immediately after the plunger to regain its normal elevated position. As is well known to those skilled in this art, this movement of the blank holder, being somewhat complicated, has usually been imparted by means of cams, and the like, which, being subject to considerable wear result in the blank holder not being held firmly to its work.

The primary object of this invention is to provide a generally improved and simplified mechanism for imparting the requisite movement to the blank holder through the medium of suitable intermediate connections such as the commonly employed oscillating levers connected by toggle links to the blank holder so that as the levers are vibrated to

bring their arms in line to the direction of movement of the blank holder, and for operating these levers, a reciprocating slide is driven from the driving or crank shaft so that during a portion of the movement of the crank shaft (in the present instance during the major portion of its revolution) the main slide will act to communicate its movement to the levers, and when said main slide and its connections have been moved to hold the blank holder to its stationary or holding position in contact with the stationary die, the movements of the crank shaft will serve only to hold the main slide and its connections in a stationary position in order to cause a pause or "dwell" of the blank holder in contact with the die.

From the above explanation it will be understood that while the present embodiment of the invention as illustrated and described herein is particularly designed and adapted for use in connection with drawing or stamping presses, the same may be readily applied and adapted for use in connection with various machines and devices where a similar or analogous movement is desired or required.

With the above mentioned and other ends in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a front elevation of the improved device or attachment as it would appear attached to the upper left-hand side of an ordinary drawing or stamping press. Fig. 2, a view of the inner side of same, showing the position of the toggle link and lever mechanism when the main slide is at the end of its stroke or in its extreme lowermost position and is about to be returned. Fig. 3, a similar view of the same when the slide is in its opposite position, the crank and lever and toggle link members being in their initial position, or in other words—in the position they occupy as the crank is about to pass through its arc of dwell at its upper dead point while the slide is in the position of a tangent or cord to this arc of dwell, and hence, during the swing of the crank through this arc (in the present instance about one-quarter of

the circle) no motion will be imparted to the slide. Fig. 4, a similar view showing the position of the crank and the lever and toggle link members at the end or conclusion of the arc of dwell.

Similar numerals of reference designate like parts throughout all the figures of the drawings.

The improved mechanical movement comprises a suitable support 1, which, however, may be a component part of the machine or device in which it is embodied, as for example—one of the vertical side members of the frame of an ordinary drawing or stamping press, the lever and toggle link members for giving the requisite movements to the main slide hereinafter described being adapted to be operated by means of a driving or crank shaft 2, the latter being provided with a crank arm 2^a, said shaft 2, being mounted, in the present instance, in a bearing arm 1^a.

The support or frame 1, is provided with bearing or guide brackets 3, adapted to guide and support the main slide 4, in its reciprocatory movements as actuated by the lever and toggle link members hereinafter described. As a means of compensating for the movements of the lever member 5, and the toggle link members 6, during the actuation of the latter through the connecting links 7, at one end of the lever 5, and the revolution of the crank arm 2^a, of the crank shaft 2, a guide member or auxiliary slide 8, is provided, said guide or auxiliary slide forming a bearing for the pivoted portion 5^a, of the lever member and the pivoted portion 6^a, of one of the toggle links so that said pivots or pins 5^a, and 6^a, of the lever 5, and the adjacent connecting link are held in fixed relation to each other during the movements of the said lever and toggle link members as clearly shown in Figs. 2, 3, and 4, of the drawings.

As a means for guiding the auxiliary slide and guide and holding the same for vertical movement in alinement with the movements of the main slide 4, bearing guide members 4^a, are formed integral with the main slide, the limits of movement of the auxiliary slide and guide being indicated by the ends of said bearing guides 4^a, and the relative movements of said auxiliary slide and guide being indicated by the arrows in Figs. 2, 3, and 4, of the drawings illustrating the movements of the lever and toggle link members, Figs. 3 and 4, showing the position of said parts at the initial and terminating portions of the arc of dwell, and the dotted lines in Fig. 3, showing the position of the parts when the crank arm 2^a, is at the center of the said arc of dwell.

It will be observed that the lower end of the lower toggle link 6, is pivotally connected to the main slide 4, in the present

instance, by means of a pivot pin 6^b, the latter being threaded in a threaded opening of a stud or boss 4^b, of the main slide 4. It will also be observed that the connecting links 7, are pivotally connected by pivot or stud pins 7^a and 7^b similar in shape to the pivot pins 5^a, 6^a, and 6^b, the pivot or stud pin 7^b, extending through the inner or connecting ends of the toggle links 6, and through the ends of the connecting links 7, as shown most clearly in Fig. 1, of the drawings.

From the foregoing description, taken in connection with the accompanying drawings, the operation and advantages of my invention will be readily understood.

Having thus described one of the embodiments of my invention, what I claim and desire to secure by Letters Patent is—

1. In a mechanical movement, a main slide, a driving shaft provided with a crank, a movable guide or slide, a pair of toggle link members, one of which is connected to said guide or slide and the other of which is connected to said main slide, a lever member pivotally mounted on said guide or slide and connected to said crank of said driving shaft, and means for connecting said lever member to said toggle links.

2. A mechanical movement, comprising a support, a main slide carried thereby, a crank shaft, an auxiliary slide adapted to reciprocate in line with said main slide, a lever member connected to said crank shaft and fulcrumed to said auxiliary slide, a pair of toggle links one of which is pivotally connected to said auxiliary slide and the other to said main slide, and a connecting link connecting said lever member to said toggle links.

3. In a mechanical movement, the combination with a main slide and an auxiliary slide adapted to reciprocate in a common direction; of a driving shaft, and lever and toggle link members pivotally connected to said auxiliary slide and driving shaft and to said auxiliary slide and said main slide, respectively, said lever member and said toggle links being connected along the common line of the reciprocation of said slides whereby said main slide is caused to dwell during a portion of the revolution of said driving shaft.

4. In a mechanical movement, the combination with a driving shaft, and a main slide and an auxiliary slide mounted to reciprocate in a common direction; of a pair of toggle links pivotally connected at their outer ends to said main and auxiliary slides and in line with the reciprocation of the latter, and a lever member fulcrumed to said auxiliary slide on a line common to pivot connections at the outer ends of said toggle links and connected to the inner ends of the latter whereby said main slide will be caused

to dwell during an arc of the revolution of said driving shaft.

5. In a mechanical movement, the combination of a crank and a main slide; of an auxiliary slide or guide mounted on and adapted to move in the direction of the latter, a connecting lever pivoted midway of its ends on said auxiliary slide or guide and having its pivoted portion movable in 10 the direction of said main slide and con-

nected at one end to said crank, and a link connected to said main slide and the opposite end of said lever.

In testimony whereof I have affixed my signature in presence of two witnesses.

WILLIAM H. WELCH.
